Primary Examiner — Jack Reickel*Assistant Examiner* — Keith J Wilson(74) *Attorney, Agent, or Firm* — Womble Bond Dickinson (US) LLP(57) **CLAIM**

The ornamental design for a shower rose, as shown and described.

DESCRIPTION

FIG. 1 is a bottom isometric view of a shower rose according to our new design;

FIG. 2 is a view of an enlarged section of the bottom isometric view of FIG. 1;

FIG. 3 is a top isometric view thereof;

FIG. 4 is a bottom view thereof;

FIG. 5 is a view of an enlarged section of the bottom view of FIG. 4;

FIG. 6 is a top view thereof; and,

FIG. 7 is a front view thereof, the rear and side views being identical to the front view.
